UNITED STATES PATENT OFFICE

OSWALD HANSEN, OF NEW YORK, N. Y.

INTERCHANGEABLE NAME PLATE

Application filed January 25, 1929. Serial No. 334,917.

This invention relates to improvements in name plates, and more particularly to a plate having a transparent window at the front and back thereof, and provided with a longitudinally extending centrally disposed channel adapted to receive any desired combination of interchangeable letters or numbers which will be visible through the windows, and will be protected from rain and other elements.

10 An object of the invention is to provide an improved name plate for use for offices, cabinet files, letter boxes, building directories and the like, which will be so arranged that interchangeable letters or numbers may be inserted within a channel in the plate behind transparent windows thereby displaying the desired indicia and at the same time protecting the same from rain, dust and finger-prints.

20 A further object of the invention is to provide an improved interchangeable name plate which will be highly efficient in use and quite inexpensive to manufacture.

Other objects will appear as the description proceeds.

25 *Drawings*

Figure 1 is a perspective view of my improved interchangeable name plate.

Figure 2 is a sectional view taken on the line 2—2 of Fig. 1.

30 Figure 3 is a sectional view taken on the line 3—3 of Fig. 2, and

Figure 4 is a front elevation of my improved interchangeable name plate, showing a portion thereof broken away to show the interior arrangement of the several parts.

35 Like characters of reference are used throughout the following specification and the accompanying drawings to designate corresponding parts.

40 *Description*

My improved interchangeable name plate comprises a casing 1, consisting of a pair of spaced reinforcing strips 2 secured in fixed 45 relation by facing sheets 3 of celluloid, which are suitably affixed at one or both sides of the said strips 2, thereby providing a longitudinally extending centrally disposed channel for the reception of the desired letters or numbers making up the preferred sign.

The celluloid sheets 3 are slit adjacent the opposite ends of the plate in line with the channel 4, and are bent outwardly to provide the guiding lips 5 to assist in the ready insertion of the letters or numbers 6 within the channel 4.

In making the desired sign, the casing 1 is supported in such a manner as to facilitate the positioning of the indicia. The letters or numbers 6 are placed at one end of the channel 4 and are guided by the lip 5 until they are supported in said channel. A filler strip 7 of substantially the same cross sectional area of the channel is then inserted in the channel after each letter 6 is placed in the end of the channel, and will be utilized to push the numbers to the desired position within the casing. After the sign is completed, a filler strip 7 will be inserted in each end of the channel until the channel is completely filled. The 65 outwardly extending portions of the strips 7 will then be filed off or otherwise separated to provide flush ends for the sign.

It will be understood that the sign can be provided with only one transparent window, 75 or with windows at opposite sides thereof as illustrated in the drawings, or can be molded from an integral piece of celluloid with transparent windows.

If the celluloid becomes scratched, or vision through the same is impaired, the sign may be turned to the opposite side and the letters reversed, thereby giving a double life to the sign.

The letters or numbers in the letter blocks 80 6 may be constructed to reflect light to add brilliance to the same, or they may be made luminous for viewing at night by the use of radium paint.

Many minor changes in detail of construction may be resorted to without departure 90 from the spirit of the invention.

I claim:

1. An interchangeable name plate provided with spaced reinforcing strips forming a longitudinally extending centrally disposed channel, transparent celluloid sheets secured to said strips at the opposite sides thereof to provide a substantially rigid casing having oppositely disposed windows, outwardly 95 100

turned guide lips formed in the sheets at the ends of said channel, and adapted to receive a plurality of interchangeable letters in said channel.

- 5 2. An interchangeable name plate provided with spaced reinforcing strips forming a longitudinally extending centrally disposed channel, transparent celluloid sheets secured to said strips at the opposite sides thereof to
- 10 provide a substantially rigid casing having oppositely disposed windows, outwardly turned guide lips formed in the sheets at the ends of said channel, and a plurality of interchangeable letters received in said channel.
- 15 3. An interchangeable name plate provided with spaced reinforcing strips forming a longitudinally extending centrally disposed channel, transparent celluloid sheets secured to said strips at the opposite sides thereof to
- 20 provide a substantially rigid casing having oppositely disposed windows, outwardly turned guide lips formed in the sheets at the ends of said channel, a plurality of interchangeable radiant letters received in said channel, and filler strips insertable in said channel at the opposite ends of said letters
- 25 and extending flush with said casing.

OSWALD HANSEN.
